UNITED STATES PATENT OFFICE.

BERNARD D. KNOWLES, OF NEW YORK, N. Y.

AUTOMATIC WRAPPING MACHINE.

Application filed May 14, 1924. Serial No. 713,143.

To all whom it may concern:

Be it known that BERNARD D. KNOWLES, a citizen of the United States, residing at 192 East End Ave., New York city, in the county of New York and State of New York, has invented certain new and useful Improvements in Automatic Wrapping Machines, of which the following is a specification.

This invention relates to a device for automatically wrapping magazines, pamphlets, papers, circulars, folders and the like which do not have stiff backs or covers. It relates more particularly to a device of this character by which the article may be bent through the middle portion and the edges brought together, by which one edge of a wrapper may be lapped or folded around one edge of the article before it is entirely folded and the other edge of the wrapper may be lapped or folded around the edges of the article after they are folded together. By this device the wrapper may be gummed and pasted during the wrapping process and the wrapper may be so applied to the article that the danger of its becoming displaced or torn off accidentally is minimized.

Heretofore wrapping machines of various sorts have been made for wrapping magazines, etc., in which, for example, the magazines were rolled up with a wrapper whose outer edge projected and was pasted down. In such cases the springiness of the paper often pulls the wrapper off unless a long time is given for the paste or glue to dry. In other machines the entire wrapper is wound, usually by a plurality of turns, around the entire article leaving a cylindrical package that is inconvenient for stacking, mailing and handling. By the present invention the article to be wrapped is folded flat and a sharp bend in the wrapper at the proper place helps to eliminate the danger of the pasted portion being torn loose by the tendency of the folded article to unfold. This and other advantages will be more clearly understood as the description proceeds. The invention will be particularly described in connection with wrapping magazines although it is to be understood that it is not confined to wrapping this article.

In the drawings:

Fig. 1 is a plan view of the middle portion of the device;

Fig. 2 is a plan view of one end;

Fig. 3 is a plan view of the other end; Fig. 4 is a section through the line 4—4 of Fig. 1;

Fig. 5 is a view showing a detail of Fig. 4; Fig. 6 is a horizontal section along the line 6—6 of Fig. 4;

Fig. 7 is a section along the line 7—7 of Fig. 1;

Fig. 8 is a section along the line 8—8 of Fig. 2;

Fig. 9 is a section along the line 9—9 of Fig. 1 or Fig. 10;

Fig. 10 is an enlarged plan view corresponding to the portion of Fig. 1 near where the sections 9, 11 and 12 are taken, this view also showing a magazine and its wrapper;

Fig. 11 is a section along the line 11—11 of Fig. 1 or Fig. 10;

Fig. 12 is a section along the line 12—12 of Fig. 1 or Fig. 10;

Fig. 13 is a section along the line 13—13 of Fig. 1 or Fig. 15;

Fig. 14 is a section along the line 14—14 of Fig. 1 or Fig. 15;

Fig. 15 is an enlarged plan view partly broken away corresponding to the portion of Fig. 1 along which the sections 13—13, 14—14 and 16—16 are taken;

Fig. 16 is a section along the line 16—16 of Fig. 1 or Fig. 15;

Fig. 17 is an enlarged plan view partly in section corresponding to the right hand portion of Fig. 2;

Fig. 18 is a section along the line 18—18 of Fig. 2 or Fig. 17;

Fig. 19 is a section along the line 19—19 of Fig. 2 or Fig. 17;

Fig. 20 is a plan view partly broken away at the ends showing a modification;

Fig. 21 is a section along the line 21—21 of Fig. 20;

Fig. 22 is a section along the line 22—22 of Fig. 20;

Fig. 23 is a section along the line 23—23 of Fig. 20; and

Fig. 24 is a section along the line 24—24 of Fig. 20.

Fig. 25 is a section along the line 25—25 of Fig. 20.

The article to be folded and wrapped, such as a magazine, for example, should be narrower than the wrapper that is to be placed around it. In the drawings, reference character 30 represents a flat table or board upon which the elements for wrapping the

articles are mounted. The right hand end of this board shown on Fig. 3 will be called the front end and the left hand end shown on Fig. 2 will be called the rear end. Parallel strips 31, L-shaped in cross section, are mounted on the board 30 to form a guide-way for the wrappers, the front ends of these strips flaring outwardly to provide a convenient entrance. These strips 31 are provided with slots through which thumb screws 32 pass so that these strips can be adjusted at different distances apart to accommodate wrappers of different widths. A number of parallel bars 33 are mounted on the top of the board 30, five being shown, two of which bars extends from one end of the board 30 to the other. A similar set of parallel bars 34 are mounted above the board 30 by means of angle irons 35 in a slightly higher plane than the bars 33. These bars serve to catch the magazine as it is dropped on top of them as will be explained below and they extend only a short distance along the board 30. Parallel strips 36, which are fastened to the board 30 by means of adjustable holders 38, serve as guides for the magazine, one of these strips 36 being provided with a wing 37 bent upwardly and outwardly to cause the magazine to drop in place when fed to the device. Stops 39 held to the board 30 by adjustable brackets 40 serve to prevent the magazine from being thrown too far to one side of the device when it is fed thereto. Two pairs of endless tapes or bands 41 are mounted so as to be within the channel formed by the guide strips 31. One endless band of each pair is above the other one. These bands pass around rollers 42 which are mounted in adjustable brackets 43 and 44 (Figs. 1 and 9), the ones at the rear end only being shown on the drawings. These bands are so disposed that the lower side of the upper one and the upper side of the lower one contact slightly so that the edges of the wrappers can be passed between them and be carried along as the bands are revolved, which can be done by any convenient means (not shown). The pairs of bands are approximately as far apart as the wrapper is wide. A sprocket chain 45 carrying extensions or lugs 46 spaced at proper distances apart passes around a driving sprocket 47 (Fig. 2) at the rear end of the device and around a loose sprocket 48 (Fig. 3) at the front end of the device. The sprocket 48 is carried by a shaft 49 which revolves in bearings 50 attached to the lower side of the board 30. The shaft 51 to which the driving sprocket 47 is rigidly attached, is mounted in bearings 52 beneath the board 30 and this shaft together with the sprocket 47 is driven by means of the driving pulley 53 from any convenient source of power. A bevel gear 54 is mounted on the shaft 51 to turn there-

with the meshes with a bevel gear 55 which is mounted on the shaft 56 to drive the same, this shaft being mounted in bearings 57 on the lower side of the board 30.

The magazines to be wrapped may be fed to the device by hand or by a suitable feed mechanism, the structure and operation of one of which will now be described. This feed mechanism which is illustrated in Figs. 1, 4 and 6 comprises four uprights or standards 60 upon which are mounted, on opposite sides, two shafts 62 that revolve in bearings 61 on the standards 60. Mitre gears 63 on the ends of the shafts 62 mesh with and are driven by mitre gears 64 on the shaft 65 which revolves in bearings 66. The shaft 65 has rigidly attached thereto a toothed wheel 67 which has the teeth on its outer periphery. A lever 68 is loosely mounted on the shaft 65 and has its outer end slotted. This lever 68 carries a pawl 69 actuated by a spring 70 to come into contact with the teeth on the toothed wheel 67. A link 71 which has its lower end adjustably mounted in the slot of the lever 68 carries a cam roller 72 near its upper end which upper end is bifurcated as shown at 74 to straddle the shaft 56 and be guided thereby. A cam 73 is mounted upon and revolves with the shaft 56 and thereby moves the link 71 longitudinally by pressing against the cam roller 72 and a spring 75 returns the link 71 which draws the same upwardly when the lower part of the cam edge is correspondingly turned, the action of the cam 73 and spring 75 thus oscillating the lever 69 and causing the wheel 67 to be turned as the pawl 69 ratchets over the teeth in one direction.

Each of the shafts 62 carries the two sprockets 77 over which endless chains 78 pass. These chains each carry at intervals horizontal bars 79 and on their inside travel they press against upright strips 80 held in place by cross pieces and at the top of the chains 78 they pass over sprocket wheels 82. Additional upright guides 81 are provided on the side of the feeding device next to the board 30.

Parallel bars 83 are joined by cross bars 84 to form a frame or rack for carrying a package or stack of magazines. This frame rests upon the bars 79 attached to the chains 78 and is gradually raised as the device is driven. The upper ends of the bars 81 are bent horizontally as shown at 85 to form a temporary rest for the magazines as they are shifted from the package stack.

At the top of the standards 60 two parallel bars 87 are fastened to form a track which extends over the board 30. A frame 88 having channels 89 along the corners thereof slides to and fro on the tracks 87. This frame 88 carries an adjustable hook or puller 90 on its rear edge. Two brack-

sets 91 carrying parallel arms 92, 93 and 94 are mounted on the front edge of the frame 88. The outer ends of the arms 94 are bent downwardly slightly and holes are provided near the outer ends of the arms 92 and 93 through which vertical rods 97 pass. These rods carry shoulders 96 against which the lower ends of expansion springs 95 rest, the other ends of these springs pressing against the under sides of the arms 92. A revoluble shaft 98 is mounted along the front side of the frame 88 and has rigidly attached thereto extensions or wings 99 and 100 upon which spring actuated pawls 101 and 102 are pivoted (see Fig. 5). The pawls 101 and 102 have inwardly bent lips to contact against the edges of the wings 99 and 100 to limit their turning in one direction. The rod 98 also carries pins 98' which project through holes near the upper ends of the rods 97 and serve to lift these rods at the proper moments. A cross piece 103 is carried by standards 104 attached to the tracks 87. An adjustable step 105 with a hole 106 near its outer end is fastened to the cross piece 103. An adjustable step 107 is mounted on the bracket arm 107' which is attached to the board 30.

A link 108 is pivoted at 109 to a lug on the front side of the frame 88 and the other end of this link is pivoted to the upper end of a lever 110 which is in turn pivoted at 111 to a lug on one of the legs 29 of the board 30. One end of the link 112 is pivoted at 113 to an intermediate portion of the lever 110 and the other end of this link 112 is adjustably pivoted by means of a crank pin 114 to the arm 115 on the gear wheel 116 which is driven by an intermediate gear 117 which in turn is driven by the gear 118 on the shaft 56.

This magazine feeder operates as follows: When the shaft 56 is revolved the cam 73 oscillates the link 71 thus causing the pawl 69 of lever 68 to turn the shaft 65 in a clockwise direction as seen in Fig. 4. The revolution of the shaft 65 drives the shafts 62 which carry the chains 73 thus causing the carrier bars 79 to rise and carry the frame 83, 84 upon which a bundle of magazines has been placed. At the same time the revolution of the shaft 56 causes through the gears 117, 116, crank arm 115 and link 112, an oscillation of the lever 119, thus drawing the frame 88 to and fro on the tracks 87. As the frame 88 moves towards the left as seen in Fig. 4, the hook 90 pushes the top magazine towards the left and causes it to rest upon the magazine rest 85. When the frame 88 moves towards the left, the pawl 102 strikes the end of the step 105 thus causing the shaft 98 to turn slightly and the pins 98' attached thereto lift the rods 97 just before the lower ends of these rods reach the edge of the

magazine. The curved end of the arm 94 projects under the edge of the magazine and when the pawl 102 reaches the hole 106 it snaps into the same thus permitting the springs 95 to push the rods 97 downwardly 70 into firm contact with the other side of the magazine. When the frame 88 is afterwards pulled towards the left, it carries the magazine therewith until the pawl 101 strikes the step 107 thereby again turning 75 the shaft 98 and causing the pins 98' to lift the rods 97 and thus release the magazine whose edge has just come into contact with the step 89. The magazine then falls flat upon the parallel bars 34 between the guides 80 36, the curved upper edge 37 of the guide 36 on the right (Fig. 4) causing the same to fall into the correct position, after which one of the projections 46 on the chain 45 pushes the magazine longitudinally of the 85 table or board 30 as described below. When a magazine is being drawn from the magazine rest 85 as just described the hook 90 is pulling another one into place on this rest and the elevating mechanism is raising the pile of magazines preparatory to another one being shifted from the top of the bundle and so on automatically to feed the magazines on to the table 30 in synchronism with the arrival of the successive 95 projections 46 on the chain 45.

An adjustable bracket 120 (Fig. 7) is attached to the top side of the board 30 and carries an arm 121 extending rearwardly a slight distance above the board 30. The bracket 120 also supports one end of the rod 122 above the board 30. A guide plate 123 (Figs. 4 and 10) for bending upwardly one edge of the wrapper is provided with a horizontal portion 124 which has a sloping edge 125. The guide plate 123 is mounted on top of the board 30 near the end of the guide 36 by means of arms 126 mounted on adjustable brackets 127. A curved guide 128 for the other edge of the wrapper is fastened at its lower end upon the top surface of the board 30 as shown at 129 and curves upwardly and inwardly, an intermediate portion being supported by the arm 130 fastened to the adjustable bracket 131 115 on the board 30.

A cam 134 on the shaft 56 (Figs. 1, 10 and 13) operates against the cam roller 135 mounted at the end of the lever 136 which is pivoted to a lug 137 on the lower side of the board 30 and projects through an opening 138, its upper end being bifurcated as shown at 139 and embracing a pin 140 on the bar 141 which is slidable in bearings 142 on the table 30. The bar 141 carries pusher plate 143 which has a concave surface for bending the magazine and a tension spring 144 serves to return the bar 141 and plate 143, one end of this spring 144 being attached to a pin 145 and the 125 130

other end being attached to the plate 143. A guide bar 150 for one edge of the magazine is provided with an outwardly curved end 151 (Fig. 10) and is fastened to the board 30 by means of adjustable brackets 152 and extends from near the plate 143 to the rear end of the board 30. A plurality of top guide bars 153 held in place by adjustable brackets 154 (Figs. 1, 10, 2, 14, 15 and 16) are retained at a sufficient distance above the board 30 to permit a folded magazine to be passed below the same.

A cam 156 (Figs. 1 and 14) mounted on the shaft 56 actuates the cam roller 157 carried by the lever 158 which projects through the opening 159 in the board 30 and is pivoted at 160 to a projection on the upper side of this board. This lever 158 carries a presser plate 161 which, at the proper moment, presses upon the folded edge of the magazine to finish folding the same. A spring 162 serves to return the lever 158 to its normal position.

A top guide plate 165 (Figs. 1, 7 and 16) for the edge of the wrapper has an upperly curved front end 166 (Fig. 7) and is held upon the board 30 by an arm 167 attached to the adjustable bracket 168. A paste applying wheel 169 is revolvably mounted beneath the guide 165 upon a shaft 171 and dips into paste contained in the container 172. The wheel 169 is attached to the shaft 171 by means of the set screw 173 so that it may be adjusted longitudinally thereof and its upper side projects through a slot or space 170 in the board 30. The shaft 171 is mounted in a bearing 176 below the board 30 and carries a bevel gear 174 which is driven by a bevel gear 175 mounted upon the shaft 56.

Plate 180 (see Figs. 2, 8 and 18) for turning downwardly the upper side of the wrapper is mounted by means of the adjustable arm 181 upon the board 30. This plate is L-shaped in cross section, the horizontal portion 182 being at the top and the vertical portion 183 terminating at its front end along a curved line 184 as shown in Fig. 8. This plate 180 bends the pasted end of the wrapper downwardly as seen in Fig. 18. Another plate for further folding the pasted edge of the wrapper is shown at 185 (Figs. 2, 8, 17 and 19) being held on the board 30 by means of the adjustable brackets 190. This plate 185 is also L-shaped in cross section. The vertical portion 186 extends outwardly at 187 (Fig. 2) at its front end and the horizontal portion 188 extends along the bottom edge of the vertical portion 186 and is beveled at its front end as shown at 189 (Fig. 2).

A shaft 195 (Figs. 1, 2, 17 and 19) is revolvably and slidably mounted in bearings 196 on the lower side of the board 30.

The shaft 195 carries a collar 197 which is straddled by a yoke 198 on the outer end of the lever 199 which is pivoted beneath the board 30 at 200 and its other end carries a pin 201 that travels in a cam groove 202 in the outer periphery of the cylindrical cam 203 which is mounted on the shaft 56. A sprocket chain 204 passes over a sprocket 205 on the shaft 56 and around the sprocket 206 on the shaft 195 to revolve the same. The lever 199 shifts the shaft 195 and the brush 207 carried thereby in a longitudinal direction. A conveyor is shown at 208 (Fig. 2) for carrying away the wrapped and sealed magazines.

The operation is as follows: A wrapper is fed to the board 30 between the guides 32 by hand or in any other convenient way and is moved along on top of the bars 33, for example, by having its edges embraced within the pairs of bands 41 which can be driven in any convenient way (not shown) until it is moved forward past wheel 48 (Fig. 3) whereupon one of the lugs 46 carried by the chain 45, will come up around the wheel 48 into contact with the rear edge of the wrapper W and the same will be continued to be moved forward. At the same time the frame 88 of the magazine feeder (Fig. 4) pulls a magazine M off of the magazine rest 85 on to the bars 34 between the guides 36 preferably with its hinge edge on the right hand side (Fig. 4). The magazine remains on the bars 34 until the projection 46 also contacts with its rear edge and moves it together with the wrapper towards the left. More than one chain 45 with lugs 46 may be provided when found to be necessary because of the width or nature of the articles to be wrapped. As soon as the magazine reaches the end of the bars 34 it drops by its own weight upon the wrapper W both being carried along the bar 30 beneath the bracket 120, arm 121 and rod 122. Soon after the wrapper and magazine reach the curved guide 128 their lower or left hand edges are beat upwardly thereby (Figs. 10 and 11) and the right hand edge of the wrapper which projects beyond the edge of the magazine is turned up and around the magazine by means of the guide plate 123 (Figs. 1, 7, 10 and 12) the rod 122 serving to prevent the middle portion of the magazine and wrapper from being lifted. About the time the lug 46 and the magazine and wrapper reach the position shown in Fig. 12, the cam 134 (Fig. 13) operates the pusher plate 143 to bring the same into contact with and press against the curved part of the magazine and wrapper thus serving to make sure that the corners of one edge of the magazine are superposed in perfect alignment with the corners of the other edge of the magazine.

Upon further forward movement the rear

curved end of the bar 128 carries the turned over sides of the magazine and wrapper into a horizontal position so that they will pass beneath the guide bars 153. At the same time the cam 156 (Figs. 1 and 14) operates the presser plate 161 so as to aid in obtaining a somewhat sharp fold or crease at the bent portion of the article. As the magazine and wrapper pass forward under the guide bars 153, the projecting upper edge of the wrapper passes underneath the guide plate 163 (Figs. 1 and 16) where the adhesive applying wheel 169 applies adhesive to the lower side of the edge of the wrapper. Upon further forward movement of the two, the edge with the adhesive applied thereto is turned at a right angle by means of the plate 180 (Figs. 2, 8 and 18), the curved edge 184 of the plate 180 effecting this result. Further forward movement of the two causes the edge with the adhesive to be bent again at right angles by the plate 185 as the beveled edge 189 and horizontal portion 188 of the plate 185 turns the same inwardly (Figs. 2, 8 and 19). When the magazine and wrapper reach the position occupied by the brush 207 (Figs. 2 and 12) this brush is revolved so as to contact with the edge of the wrapper and wipe across the same so as to stick it to the outside of another portion of the wrapper. The brush 207 is driven to wipe across the edge of the wrapper in a direction tending to wrap the same more tightly around the package and at the same time the lever 200 (Fig. 1) lifts the brush corresponding to the forward movement of the wrapper so as to eliminate any tendency for the brush to draw backwards and cause the edge of the wrapper to become stuck in an askew position. During the travel of the magazine and wrapper from the position where the plate 143 (Fig. 1) contacts therewith, they are prevented from being displaced by the rod 122 and guide 150 (Figs. 1, 2, 13 to 19). The magazine with its wrapper sealed therearound is then carried to the end of the board 30 and may be thrown on to a conveyor 208 and be carried away to the desired point.

In the modification shown in Figs. 20 to 23, a table or board 250 is provided with a longitudinal channel 249 through which a chain 251 carrying pairs of pivoted projections 252 at predetermined intervals is caused to pass by being driven in any convenient way. Guides 253 for a wrapper and guides 254 for a magazine are provided and near the ends of these guides are placed curved guideways 255 and 256 which are spaced apart and form, in effect, a wide curved trough. An adjustable folding strip or cam 257 is mounted near the front end of the guide 256. Brackets 258 and 259 carrying vertical parallel aligned wheels 260 and 261 are mounted upon the board 250. The guide way 256 has a horizontally pro-

jecting portion 262 and a depending lip 263 at its upper edge (Figs. 20 and 23) to form a channel and the guideway 255 gradually curves upwardly and inwardly and has a horizontally projecting portion or lip 264 at its upper edge. A wheel 266 is mounted beneath the lip 264 to dip into the adhesive contained in the receptacle 267. The forward portion of the guide way 255 beyond the lip 264 is bent downwardly as shown at 268 (Figs. 20 and 25) and an opening 269 is provided therein for the purpose of permitting the ends of the elements 270 of the brush 271 to pass therethrough as the brush is revolved.

The operation is as follows: A magazine wrapper Wr is placed between the guides 253 and a magazine Mz is placed thereon between the guides 254 and then the pivoted projections 252 carried by the chain 251 are brought into contact with their rear edges to move them forward. As they are moved forward the central portion thereof passes beneath the wheels 260 and 261 and are prevented from being raised while their edges are curved upwardly (Fig. 22) and also while the cam 257 turns the extreme edge of the wrapper at a right angle. As the two are moved forward to the position shown in Fig. 23, both sides are turned into a substantially vertical position and the extreme right hand edge of the wrapper is further bent at a right angle by means of the depending lip 263. Further forward movement of the two to the position shown in Fig. 24 causes the left hand edge of the wrapper to be bent horizontally by means of the horizontal portion 264 (Fig. 24) of the guide 255 and when it passes over the wheel 266 the adhesive is applied to the lower side thereof. Further forward movement of the two causes the downwardly projecting portion 268 of the guide 255 (Fig. 25) to turn the edge of the wrapper downwardly after it has passed beyond the end of the guide 256. Brush 271 then brushes through the opening 269 against the overlapping edge of the wrapper and causes the same to be stuck. During the time the projections 252, carried by the chain 251, are moving the magazine and wrapper through the channel formed by the guideways 255 and 256, they are gradually turned upwardly as more clearly shown in Fig. 24 by the gradually curving portions of the guideways 255 and 256 and again drop into open position when they have passed beyond the channel formed by these guideways.

I claim:

1. In a device of the character described, means for moving an article and wrapper therefor together longitudinally, means for folding them along a longitudinal line and means for bending one edge of the wrapper around both edges of the folded article.

2. In a device of the character described, means for moving an article and wrapper therefor together longitudinally, means for folding them along a longitudinal line and means for applying an adhesive along one edge of the wrapper and means for bending it around both edges of the folded article. 70
3. In a device of the character described, means for moving an article and wrapper therefor together longitudinally, means for folding them along a longitudinal line and means to bend one edge of the wrapper around one edge of the article and means to bend the other edge of the wrapper around both edges of the article. 75
4. In a device of the character described, means for moving an article and wrapper therefor together longitudinally, curved members for folding said article along a single longitudinal line and means for bending one edge of the wrapper around both edges of the folded article. 80
5. In a device of the character described, means for moving an article and wrapper therefor together longitudinally, means for folding said article along a single longitudinal line and a stationary guide for bending one edge of the wrapper around both edges of the folded article. 85
6. In a device of the character described, means for moving an article and wrapper therefor together longitudinally, means for folding said article along a single longitudinal line and a stationary guide to bend one edge of the wrapper around one edge of the article and a second stationary guide to bend the other edge of the wrapper around both edges of the article. 90
7. In a device of the character described, means for moving an article and wrapper therefor together longitudinally, means for folding them along a longitudinal line and means to bend one edge of the wrapper around one edge of the article and means to apply adhesive along the other edge of the wrapper and means for bending it around both edges of the article. 95
8. In an automatic wrapping machine for flexible articles, a board, an endless chain with projections thereon for moving an article longitudinally along said board, means to prevent the medial portion of said article from being raised and means to bring the edges of said article together as it is being moved longitudinally. 100
9. In an automatic wrapping machine for flexible articles a board, means for moving an article longitudinally along said board, a longitudinal rod above said board to prevent the medial portion of said article from being raised and means to bring the edges of said article together as it is being moved longitudinally. 110
10. In an automatic wrapping machine for flexible articles, a board, combination, a device for feeding articles to said board, means for moving an article longitudinally along said board, means to prevent the medial portion of said article from being raised and means to bring the edges of said article together as it is being moved longitudinally and a common driving means for said feeder and said means for moving the article longitudinally. 115
11. In an automatic wrapping machine for flexible articles, a board, means for moving an article and a wrapper therefor longitudinally and folding the article in a single fold, and means to apply adhesive along one edge of the wrapper and means to turn the edge of the wrapper around the edges of the article. 120
12. In an automatic wrapping machine for flexible articles, a board, means for moving an article and a wrapper therefor longitudinally along said board and folding in a single longitudinal fold, and means to apply adhesive along one edge of the wrapper, means to turn the edge of the wrapper around the edges of the article and means temporarily moving longitudinally with said article to press said edge firmly against the outside of the wrapper. 125
13. In an automatic wrapping machine for flexible articles, a board, means for moving an article and a wrapper therefor longitudinally and folding the article in a single longitudinal fold, and means to apply adhesive along one edge of the wrapper, means to turn the edge of the wrapper around the edges of the article and a brush temporarily moving with said article to press said edge firmly against the outside of the wrapper. 130
14. In an automatic wrapping machine for flexible articles, a board, means for moving an article and a wrapper therefor longitudinally and curved guides for folding the article in a single longitudinal fold, and means to apply adhesive along one edge of the wrapper and means to turn the edge of the wrapper around the edges of the article. 135
15. In an automatic wrapping machine for flat flexible articles, a board, a chain with projections thereon for moving an article and a wrapper therefor longitudinally along said board, a medial longitudinal member beneath which said article and wrapper are moved, means for folding said article along a medial line, a stationary guide for turning one edge of said wrapper around one edge of said article, a wheel for applying adhesive to the other edge of said wrapper, a stationary guide for turning said other edge of said wrapper around both edges of said article, a brush for wiping said edge against another portion of said wrapper and means for moving said brush longitudinally with said article while it is wiping said edge. 140
16. In an automatic wrapping machine for flexible articles, a board, combination, 136

for flat flexible articles, a board, a chain with projections thereon for moving an article and a wrapper therefor longitudinally along said board, a medial longitudinal member beneath which said article and wrapper are moved, means for folding said article along a medial line, a stationary guide for turning one edge of said wrapper around one edge of said article, a wheel for applying adhesive to the other edge of said wrapper, a stationary guide for turning said other edge of said wrapper around both edges of said article, a brush for wiping said edge against another portion of said wrapper, means for moving said brush longitudinally with said article while it is wiping said edge, and a common driving means for said chain and brush.

17. In the process of folding and wrapping flexible articles, the steps which comprise placing an article and wrapper together, moving the two longitudinally, folding the two along a longitudinal line and bending one edge of the wrapper around both edges of the article.

18. In the process of folding and wrapping flexible articles, the steps which comprise placing an article and wrapper together, moving the two longitudinally, folding the two along a longitudinal line, applying adhesive near one edge of the wrapper and bending said edge of the wrapper around both edges of the article.

19. In the process of folding and wrapping flexible articles, the steps which comprise placing an article and wrapper together, moving the two longitudinally, folding the two along a longitudinal line and bending one edge of the wrapper around one

edge of the article and turning the other 40 edge of the wrapper around both edges of the article.

20. In the process of folding and wrapping flexible articles, the steps which comprise placing an article and wrapper together, moving the two longitudinally, folding the two along a longitudinal line, forcing the two edges of the article together and bending one edge of the wrapper around one edge of the article and turning 50 the other edge of the wrapper around both edges of the article.

21. In the process of folding and wrapping flexible articles, the steps which comprise placing an article and wrapper together, moving the two longitudinally, folding the two along a longitudinal line, applying adhesive near one edge of the wrapper, bending said edge of the wrapper around both edges of the article and pressing 60 the portion of the wrapper with adhesive thereon against the outside of said wrapper.

22. In the process of folding and wrapping flexible articles, the steps which comprise placing an article and wrapper together, moving the two longitudinally, folding the two along a longitudinal line, applying adhesive near one edge of the wrapper, bending said edge of the wrapper 70 around both edges of the article and pressing the portion of the wrapper with adhesive thereon against the outside of said wrapper in a direction tending to tighten 75 the wrapper.

In testimony whereof I affix my signature.

BERNARD D. KNOWLES.
